John H. Royall
INVENTOR

BY Victor J. Evans

ATTORNEY

J. H. Royall, Jr.
WITNESS:

UNITED STATES PATENT OFFICE.

JOHN H. ROYALL, OF PHILADELPHIA, PENNSYLVANIA, ASSIGNOR TO PERRY E. BEAM, OF ST. DAVIDS, PENNSYLVANIA.

TIPPING MACHINE.

Application filed May 3, 1924. Serial No. 710,917.

To all whom it may concern:

Be it known that I, JOHN H. ROYALL, a citizen of the United States, residing at Philadelphia, in the county of Philadelphia and State of Pennsylvania, have invented new and useful Improvements in Tipping Machines, of which the following is a specification.

This invention relates to tipping machines and particularly to machines for placing tips on shoe laces. One of the principal objects of the device is to provide tip clinching jaws which shall move directly toward and from each other and which always remain in parallel relation with each other.

Another object is to form the jaws with teeth which shall interlock so as to ensure a perfect operation.

Another object is to produce a device of this nature which shall be simple of construction, cheap to manufacture, and highly efficient for the purpose for which it is devised.

With these and other objects in view as will be more apparent hereinafter, the invention consists in certain novel construction and combination and arrangement of parts, the essential features of which are hereinafter fully described, are particularly pointed out in the appended claims, and are illustrated in the accompanying drawing, in which:—

Figure 1—is a side elevation of my improved tipping machine.

Figure 2—is a front end elevation of the same.

Figure 3—is a detail top plan view of one of the dies or jaws.

Figure 4—is an end view of the device in operative position.

Like characters of reference refer to like parts in all the views.

Referring to the drawing in detail, 10 and 11 represent handles, each of which terminates in a respective pair of fingers 12 and 13. Between the fingers 12 of the handle 10 is pivoted a jaw 14, the pivot being shown at 15. Similarly a jaw 16 is pivoted to the fingers 13 at 17. Each of the jaws 14 and 16 is bifurcated at its rear end to straddle re-

spective pins 18 and 19 carried by the fingers 13 and 12, respectively.

The jaws 16 and 14 are provided with a plurality of teeth 20 which extend transversely of the jaws and which are formed with V-shaped notches 21, terminating in curvilinear portions 22. The teeth of the jaws are staggered so as to interlock when the jaws are brought together.

At the back of the jaws are two teeth 30 of half the height of teeth 20 and considerably broader. These two teeth meet and are provided with a taper way 31 as shown in Figure 3.

In use, the lace with the tip is placed between the jaws, and then the handles 10 and 11 are squeezed together whereby the teeth 20 are brought into interlocked relation and pressed home until they assume the position shown in Figure 4 at which time they have completely closed the tip on the lace and have crimped it at the intersection of each pair of teeth, the back teeth 30 making a tapered end on the tip.

While I have described what I deem to be the most desirable embodiment of my invention, I do not limit myself to the specific details of construction or material, nor to anything less than the whole of my invention as defined in the appended claims.

What I claim is:—

1. A tipping device comprising a pair of jaws, teeth arranged thereon, the teeth of one jaw being staggered with relation to the teeth of the other jaw, a short broad tooth on each jaw adjacent to the innermost first named tooth, said short broad teeth provided with tapered ways in their facing surfaces for tapering the end of a tip.

2. A tipping device comprising a pair of jaws, teeth arranged thereon and having V-shaped notches, the notches in the teeth of one jaw aligning with the notches in the teeth of the other jaw, the teeth of one jaw being staggered with relation to the teeth of the other jaw, a short broad tooth on each jaw adjacent to the innermost first named teeth, said short broad teeth provided with tapered ways in their facing surfaces for tapering the end of a tip, and means for moving said

jaws to bring the teeth into interlocked relationship.

3. A tipping device comprising a pair of jaws, teeth arranged thereon and having V-shaped notches, the notches in the teeth of one jaw aligning with the notches in the teeth of the other jaw, the teeth of one jaw being staggered with relation to the teeth of the other jaw, a short broad tooth on each

jaw adjacent to the innermost first named teeth, said short broad teeth provided with tapered ways in their facing surfaces for tapering the end of a tip, and means for moving said jaws to bring the teeth into interlocked relationship and parallel one to the other.

In testimony whereof I affix my signature.

JOHN H. ROYALL.
